CLAIM

The ornamental design for a mobile phone, as shown and described.

DESCRIPTION

FIG. 1 is a front perspective view of a mobile phone showing our new design, in which the cover has been attached to the front side of the subject design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a rear perspective view thereof in which the cover has been attached to the rear side of the subject design;

FIG. 9 is a front view thereof that includes a broken line example of the mobile phone in an operating state;

FIG. 10 is a front perspective view thereof in which the cover has been shown attached and slid down;

FIG. 11 is a front view of FIG. 10;

FIG. 12 is a rear view of FIG. 10;

FIG. 13 is a left side view of FIG. 10;

FIG. 14 is a right side view of FIG. 10; and,

FIG. 15 is a front view of FIG. 10 that includes a broken line example of the mobile phone in an operating state.

The broken lines shown in the figures that are immediately adjacent to the areas included in the claim and define unshaded regions represent the bounds of the claim. All other broken lines, including those within broken line boundaries, the display rectangle, the features to either side of the speaker at the top front, and the displayed images, are directed to environment. The broken lines form no part of the claimed design.
